UNITED STATES PATENT OFFICE

JOHN H. HUNT, OF DETROIT, MICHIGAN, ASSIGNOR TO GENERAL MOTORS RESEARCH CORPORATION, OF DETROIT, MICHIGAN, A CORPORATION OF DELAWARE

REFLECTOR

Application filed September 1, 1927. Serial No. 216,901.

This invention relates to reflectors and more particularly to a reflector for use in a headlight of an automotive vehicle.

The broad objects of the invention are to provide a reflector which will produce the desired light pattern and which is capable of being reproduced accurately and easily, simply by a statement of dimensions.

It is an object of this invention to combine a paraboloidal or hyperboloidal surface with an ellipsoidal surface to produce a reflector of the type desired. In order to adapt a paraboloidal or hyperboloidal reflector for use with a two filament bulb, the upper part of the reflector must be modified to cast the light generally downward so that the top of the beam will be responsive to a change from one filament to the other. With the upper part of the reflector elliptic, the light will be cast downward as desired, the source of light being at the focus.

There are several objects in view in combining the surfaces referred to. One advantage is that it provides a deeper light, that is, a greater vertical depth of beam without shifting the position of maximum candle power in the beam. A further important feature of my invention resides in the fact that one reflector may have several zones which may be hyperboloidal, paraboloidal or ellipsoidal, and with the focal length the same and the source of light at or near the focus, the beam or pattern produced by a reflector of any given dimensions can be fairly closely calculated. In other words, it is not a hit and miss proposition, as the problem is simplified by the fact that one of the factors, that is, the focal length, is a constant. This enables the designer to secure a pattern of the desired shape and intensity by varying the eccentricity of the hyperboloidal or ellipsoidal surfaces.

Since the problem is one of combining an ellipsoidal surface with a surface which may be either paraboloidal or hyperboloidal but which may not be ellipsoidal, I have used the term "open figure" to include a parabola or hyperbola, but not to include an ellipse.

Other objects of the invention will appear in the course of the following description,

taken in connection with the accompanying drawing and appended claims.

In the drawing:

Figure 1 is a front view of the punch for forming by improved reflector. 55

Figure 2 is a side elevation of the punch.

Figure 3 is a horizontal section through the center of the punch after it has been striped or zoned.

Figure 4 is a front view of a reflector 60 formed with my improved punch.

Figure 5 is a section on the line 5—5 of Figure 4.

The form of my improved reflector is best understood by a description of the method 65 of making the punch. The first operation consists in turning a surface of revolution on a blank. The surface may be a paraboloid or it may be hyperboloid with a fairly low eccentricity. While a parabolic 70 reflector with the light at the focus may be theoretically the most desirable, still the light source is never the theoretical point and for this reason, I do not wish to be limited to a particular geometric surface of 75 revolution. The surface of revolution is theoretically generated by revolution of the curve indicated by the dotted line 1 in Figure 2 and the axis of revolution is denoted by reference character 10. The lower 80 punch marked 11 is thus produced and remains unchanged, the modifications being made in the upper part of the punch.

The next operation resides in modifying 85 the upper part of the reflector by means of an elliptic curve. This is done by taking an ellipse of the same focal length as the original parabola or hyperbola and superimposing it thereon. The foci and vertices 90 of the two curves then coincide while the top of the figure is dropped the distance between the points 4 and 5. The ellipse is then rotated about axis 20 parallel with but spaced below the axis 10 the distance between the points 4 and 5.

This method produces a surface 22 above the line 12 whose radial sections are elliptical with foci falling on a semicircle whose radius is equal to the distance the axis of 120

rotation 20 is offset from the axis 10 of the punch. By increasing the amount of the offset of these two axes a smaller proportion of the surface of the punch will be modified.

5 The top of the punch is then bent down still further. This may be done in any way thought desirable. It may be done by employing a second ellipse or other curve 3 having its focus and vertex coinciding with the focus and vertex of the original 10 parabola 1 and rotating curve 3 about axis 30 producing the area 33 brought further within the limits of the original paraboloid. If the ellipse is of sufficiently low eccentricity, this third zone will not be necessary.

15 With the punch in this condition a plain reflector can be produced for use with a vertically fluted lens. I have illustrated my invention, however, as applied to a fluted reflector. Figure 3 illustrates the arrangement of the vertical flutes 7 on the punch. The reflector formed from this punch is shown in Figures 4 and 5. As illustrated in these figures and in Figure 2, there are 20 three zones to the reflector. Disregarding the flutes the lower zone 11, beneath the lines 12, is part of the original surface of revolution and is hyperboloidal or paraboloidal as described in detail above. The 25 second zone 22, above line 12 and below line 23, is elliptic as described above. The third zone 33, which is above the line 23, may be a surface of any shape which throws the light still lower than the second zone. 30 35 The vertical flutes 7 merely effect a lateral spreading of the beam and, as indicated above, this is not an essential feature of my invention as the lateral spread can be secured by leaving the surface of the reflector plain and using a vertically fluted lens.

40 It is to be understood that the terms "above," "below," "top," and "bottom" as used in this application are relative terms only. If the headlamp is used for some 45 other purpose than road lighting, or if State requirements as to light distribution are changed, it may obviously be desirable to turn or tilt the lamp in one direction, or the other. Such changes would not, however, affect the relative location of the parts 50 of the reflector with respect to each other and consequently would not take the construction outside of the scope of the appended claims.

55 I claim:

1. A reflector comprising a substantially paraboloidal lower portion, an intermediate portion joining the lower portion without abrupt break in curvature, said intermediate 60 portion being formed by the rotation of an ellipse about an axis displaced below the axis of the lower portion, and an upper portion bent downwardly with respect to said lower and immediate portions.

65 2. A reflector the lower portion of which is

a surface generated by the rotation of an open curve of a conic section about its axis, and the upper portion of which is a converging focalizing surface generated by the rotation of a curve of conic section of less eccentricity than the first named curve about an axis parallel to and below the axis of the former and so offset therefrom that the generated surfaces will intersect in curved lines above a horizontal plane passing through the axis 70 of generation of the lower surface; the generating curve of the upper portion of the reflector when in the vertical plane having its focus and vertex coincident substantially with the focus and vertex of the generating 75 curve of the lower portion of the reflector.

In testimony whereof I affix my signature.

JOHN H. HUNT.
